BALLERINA DOLL

Ruth Lambertz, San Francisco, Calif.

Application May 20, 1947, Serial No. 139,159

Term of patent 7 years

(Cl. D34—4)

To all whom it may concern:

Be it known that I, Ruth Lambertz, a citizen of the United States, residing at San Francisco, county of San Francisco, State of California, have invented a new, original, and ornamental Design for Ballerina Dolls, of which the following is a specification, reference being had to the accompanying drawing, forming part thereof.

I claim:

The ornamental design for a ballerina doll, as shown.

RUTH LAMBERTZ.
